DESIGN FOR A CLOTHES HANGER

Dee R. Anderson, Western Springs, Ill.

Application March 1, 1945, Serial No. 118,204

Term of patent 14 years

(Cl. D80—8)

To all whom it may concern:

Be it known that I, Dee R. Anderson, a citizen of the United States and resident of Western Springs, in the county of Cook and State of Illinois, have invented a new, original, and ornamental Design for a Clothes Hanger, of which the following is a specification, reference being had to the accompanying drawing, forming a part thereof.

The figure on the drawing is a perspective view of a clothes hanger showing my new design.

I claim:

The ornamental design for a clothes hanger, as shown.

DEE R. ANDERSON.
